US0D1033029S

(12) **United States Design Patent** (10) **Patent No.:** **US D1,033,029 S**
(45) **Date of Patent:** **** Jul. 2, 2024**

(54) **SHOE ORTHOTIC**

- (71) **Applicant:** **Hewlett-Packard Development Company, L.P.**, Spring, TX (US)
- (72) **Inventors:** **Kai Halsinger**, Vancouver, WA (US); **Nathan Eric Shirley**, Vancouver, WA (US); **Melanie Shelton**, Vancouver, WA (US); **Felix Ballerstedt**, Portland, OR (US); **Evan Lloyd Greenberg**, Portland, OR (US); **Robert Michael Bruce**, Portland, OR (US); **Ronnie George Parsons**, Portland, OR (US)
- (73) **Assignee:** **Hewlett-Packard Development Company, L.P.**, Spring, TX (US)
- (**) **Term:** **15 Years**
- (21) **Appl. No.:** **29/896,878**
- (22) **Filed:** **Jul. 9, 2023**

(57) **CLAIM**

The ornamental design for “shoe orthotic,” as shown and described.

DESCRIPTION

This patent or application file contains at least one drawing executed in color. Copies of this patent or patent application publication with color drawing(s) will be provided by the Office upon request and payment of the necessary fee.

FIG. 1 is a perspective view of bottom of a first shoe orthotic insert over a top of a second shoe orthotic insert.

FIG. 2 is a bottom, rear perspective view of the first shoe orthotic insert of FIG. 1.

FIG. 3 is a top, rear perspective view of the first shoe orthotic insert of FIG. 1.

FIGS. 4A and 4B are top views of the first and second shoe orthotic inserts of FIG. 1, respectively.

FIGS. 5A and 5B are top views of the first and second shoe orthotic inserts of FIG. 1, respectively in an alternative color; and,

FIG. 6 is an exploded view of the first shoe orthotic insert of FIG. 1.

1 Claim, 6 Drawing Sheets
(6 of 6 Drawing Sheet(s) Filed in Color)
